US00D993974S

(12) **United States Design Patent** (10) Patent No.: **US D993,974 S**
(45) Date of Patent: **** Aug. 1, 2023**

(54) **DISPLAY SCREEN OR PORTION THEREOF
WITH GRAPHICAL USER INTERFACE**

- (71) Applicant: **Apple Inc.**, Cupertino, CA (US)
- (72) Inventors: **Alan C. Dye**, San Francisco, CA (US);
Joseph Mark Willoughby Luxton, San
Francisco, CA (US)
- (73) Assignee: **Apple Inc.**, Cupertino, CA (US)
- (**) Term: **15 Years**
- (21) Appl. No.: **29/820,589**
- (22) Filed: **Dec. 22, 2021**

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is another embodiment thereof.

The broken lines in the figures show a display screen or portion thereof, and form no part of the claimed design.
